TIMING RELAY MECHANISM

Ellis G. Powell, Michigan City, Ind., assignor to
 C. A. Dunham Company, Marshalltown, Iowa,
 a corporation of Iowa

Application February 26, 1934, Serial No. 713,001

20 Claims. (Cl. 236—74)

This invention relates to a new and improved timing relay mechanism, and more particularly to a mechanism for controlling the movement of a motor so that the device actuated thereby may be moved slowly from one position to another.

It is frequently desirable to adjust a part slowly from one position to another. For example, in a steam heating system where the steam is supplied from a central station, it is desirable to open the main steam valve slowly so as to avoid the "peak" that would be caused by suddenly throwing the full demand of the entire cold heating system onto the supply main. By gradually opening this main steam valve, regardless of what the initial demands of the heating system may be, this peak is avoided. In other lines of work it is often desirable to bring the equipment up to temperature gradually and to maintain it at this temperature for a given length of time. In such cases a time switch governs the opening and closing of the valve, and in addition a timing device is desirable to control the rate at which the valve is opened and closed.

Where the valve, or other mechanism, is operated by an electric motor it is often impractical to provide sufficient gear reduction so that the valve may be moved with sufficient slowness from a continuously rotating motor. According to the present invention the actuating motor is rotated intermittently, step by step, so as to gradually spread the valve opening or closing movement over a considerable length of time. The motor, which is reversible, is provided with a pair of actuating circuits one for moving the motor in each direction. A circuit maker and breaker is adapted to intermittently open and close one of these circuits (in accordance with the desired direction of rotation of the motor), and this circuit maker and breaker is actuated by an electro-magnetic device the actuating circuits for which are controlled by a pair of adjustable resistance devices which are balanced when the motor is at rest. Each of these resistance devices comprises a movable contact member whereby the effective value of the resistance may be varied, and the movable contact of the control resistance is slowly moved by means of a thermostatically actuated mechanism responsive to the heat developed by an adjustable electric heating element. The movable contact of the other balancing resistance is adjusted more rapidly by the motor so as to successively balance the control resistance as this control resistance is gradually adjusted, and thus cause the motor

to be moved slowly, step by step, throughout its range of valve-actuating movement.

The principal object of this invention is to provide a means for controlling the rate of movement of a valve or similar device, as briefly described hereinabove and disclosed more in detail in the specifications which follow.

Another object is to provide an electrically operated timing device which may be operated at low potential so that the device may be located remote to the valve-operating device which it controls and which may be run at a minimum of expense.

Another object is to provide such a timing device which is adjustable so that the rate of movement of the actuated element may be varied within the maximum timing interval.

Another object is to provide a device of this kind which is simple, inexpensive in construction, and reliable in operation.

Other objects and advantages of this invention will be more apparent from the following detail description of one approved form of mechanism constructed and operating according to the principles of this invention.

In the accompanying drawings:

Fig. 1 is a diagrammatic view illustrating the principal elements of the timing mechanism, and the wiring connections therefor.

Fig. 2 is a diagrammatic elevation showing a typical heating system with this timing control mechanism applied thereto.

Reference will first be made to Fig. 2 which shows a typical steam heating system which is supplied with steam through the branch main D leading from a central station or other suitable source of steam supply.

This supply main D may be provided near its inlet end with a steam-separator 1, a normally open cut-off or gate valve 2, and an automatic reducing valve 4 which may be either manually or thermostatically adjusted to reduce the pressure and temperature of the steam before it is delivered to the radiating system. The reduced pressure steam is delivered through risers 5 into the radiators 6 provided at their outlets with steam traps 7 through which condensate and non-condensable gases are drawn out into the return pipe 8 which leads to a suitable exhausting mechanism indicated generally at E which serves to withdraw and vent the non-condensable gases, collect the condensate and deliver it to a suitable receptacle, and maintain a lower pressure in the return pipe 8 than in the radiators 6 so as to assure the evacuation

of the radiators. The actuating motor 9 for the exhausting apparatus E is controlled by a differential-pressure controller 10 and a float-controlled switch 11. The power for operating this electrical apparatus is delivered through the mains 12 and 13 provided with the main cut-out switch 14. The heating system thus briefly described by way of example is of the sub-atmospheric differential-pressure type disclosed in several prior art patents, for example the patent to Clayton A. Dunham No. 1,644,114, granted October 4, 1927. As far as the present invention is concerned, any approved type of heating system could be supplied with steam from the supply main D. At 3 is indicated a motor-operated cut-off valve positioned in the supply main D, the present invention being particularly concerned with the automatic control and operation of this valve 3.

It will now be apparent that if this heating system is cold and the main valve 3 is quickly and completely opened, there will be a sudden rush of steam into the heating system which steam will be quickly condensed so as to cause a protracted demand on the steam supply, this demand greatly exceeding the "normal demand", that is the amount of steam required to keep the radiating system filled after the system is once heated up and in normal operation. In order to avoid this excessive demand or peak load, means is provided for opening the valve 3 very slowly so as to cut down the initial supply of steam to the heating system and not permit a free flow of steam through the main D until the system has been heated up to approximately the normal operating temperature.

The valve 3 is opened and closed by a motor mechanism indicated generally at A, this motor being controlled by a system of relay devices in the panel board B, which relay mechanism is in turn controlled jointly by the timing-switch mechanism C and the motor A. The opening or closing of valve 3 is initiated through the timing mechanism C by means of a suitable circuit making and breaking device such as the manually operable switch 15, a thermostat 16, or a time-operated switch 17. Any one or all of these devices may control the timing mechanism C, it only being necessary that some device be used to close a circuit when it is desired that the valve 3 be opened and to break this circuit when the valve is to be closed. The construction and operation of the devices A, B and C will now be better understood by referring to the diagrammatic showing in Fig. 1. The motor assembly A comprises the motor A', preferably a small single phase alternating current motor, which is equipped with two sets of windings, one for clockwise and the other for counter-clockwise rotation. This motor is adapted, through suitable reduction gearing, to open or close the valve 3 (Fig. 1) or to operate any other suitable device. Within the motor case a reduction gearing connects the rotor of the motor to a shaft 18 upon which is mounted the crank arm 19 having the pin and slot connection 20 with one arm of a lever 21 intermediately pivoted at 22. The other arm of this lever carries the movable contact 23 of the balancing resistance device indicated generally at X. This device comprises a suitable arcuate resistance member connected between the two terminals 24 and 25 and adapted to be divided into two effective portions by the movable contact device 23. Wires 26, 27 and 28 lead

from the two terminals 24 and 25 of the resistance and the movable contact 23 to the three terminals 29, 31 and 30 respectively on the relay panel B.

Wires 32 and 33 lead respectively from the power mains 12 and 13 to the binding posts 34 and 35 on relay panel B. A wire 36 connects binding post 34 with one terminal 37 on the motor A. Wire 38 leads from binding post 35 to the spring arm 39 which carries the central movable contact 40 of a motor-control switch F. This switch mechanism also comprises a pair of adjustably mounted fixed contacts 41 and 42 between which the contact 40 is positioned so as to be out of engagement with both fixed contacts when in neutral position. Movement of contact 40 to the left will engage fixed contact 41, and movement to the right will engage fixed contact 42. The contacts 41 and 42 are connected respectively by wires 43 and 44 with the terminals 45 and 46 on the panel board, which in turn are connected by wires 47 and 48 with the terminals 50 and 51 of motor A'. One winding of motor A' (for example, the winding which will cause clockwise rotation) is connected between the terminals 50 and 37, whereas the other winding (for example, for causing counter clockwise rotation) is connected between the terminals 51 and 37. Therefore it will be seen that when the movable contact 40 of control switch F is moved into engagement with fixed contact 41 the motor A' will rotate in one direction, for example clockwise, and that when movable contact 40 is moved into engagement with fixed contact 42 the motor will rotate in the opposite direction. When movable contact 40 of switch F is in the central or neutral position the motor A' will be at rest.

The primary coil 52 of transformer G is energized through wires 53 and 54 connected respectively to power terminals 34 and 35. The secondary 55 of transformer G furnishes low-voltage current suitable for operating the relay mechanism through wires 56 and 57 to the central terminals 58 and 59 respectively. Binding post 58 is connected through wire 60 and protective resistance 61 with terminal 31, and binding post 59 is similarly connected through wire 62 and protective resistance 63 with the terminal 29. Binding posts 58 and 59 are respectively connected by wires 64 and 65 with the two terminals of coil 66 of a balanced solenoid H. A centrally tapped terminal 67 of the solenoid coil 66 is connected through wire 68 with the panel terminal 30. The core 69 of solenoid H is connected through stem 70 and spring connection 71 with the flexible spring arm 12 which carries the central contact member 73 of the switch mechanism J. The contact 73 is positioned between and is adapted to engage alternatively with the adjustably fixed contacts 74 and 75 of this switch J. The fixed contact 74 is connected through wire 76 with a terminal 77 tapped onto a few end turns of the solenoid coil 66. In a similar manner switch terminal 75 is connected through wire 78 with a terminal 79 tapped onto a few turns at the opposite end of solenoid coil 66. The end terminals of coil 80 of a second balanced solenoid K are connected by wires 81 and 82 with the power binding posts 58 and 59 respectively. A terminal 83 tapped into the central portion of coil 80 is connected through wire 84 and protective resistance 84' to the flexible support 12 for movable contact 73 of switch J. The core 85 of balanced solenoid K is connected through stem 86 with the

free end of spring support 39 for the movable contact 40 of motor-switch F. When a current of uniform strength is flowing through all parts of solenoid coil 80, the core 85 will be held in the central position shown in Fig. 1, thus moving contact 40 to its central neutral position out of engagement with either contact 41 or 42, and the motor A' will be at rest. Similarly, when the current is equal in all sections of solenoid coil 66 10 of the balanced solenoid H, the core 69 will be held in the central position shown in the drawings, and the switch mechanism J will be in off or neutral position.

The timing mechanism C comprises a control resistance Y which is similar to the balancing resistance X already described, these resistances being equal and equally distributed between the end terminals thereof. The end terminals 87 and 88 of resistance Y are connected by wires 89 and 90 to the terminal binding posts 91 and 92 respectively, these binding posts being connected through wires 93 and 94 to the terminals 31 and 29 on the panel board B. The movable contact member 85 of control resistance Y is (in the example here shown) mounted at the free end of a thermostatic bar 96 fixed at its other end 97. When bar 96 is cold or at normal room temperature, it will extend in the position shown in solid lines so as to hold movable contact 95 at one end of the control resistance, that is substantially at the terminal 81. When this thermostatic bar 96 is sufficiently heated, it will warp into the position shown in dotted lines so as to move the contact 95 to the other end of the resistance, that is substantially into engagement with terminal 86.

Movable contact 95 is connected through bar 96 and wire 98 with binding post 99 which is connected through wire 100 with the terminal 30 on panel board B.

40 The thermostatic bar 96 is surrounded by or closely associated with a suitable electric heating element here shown as consisting of the four heating elements 101, 102, 103 and 104 connected in parallel between the wires 105 and 106 of the heating circuit. Wires 107 and 108 extend from the power mains 12 and 13 to the binding posts 109 and 110 on the timing unit C. Binding post 109 is connected through wire 111 to one terminal of the primary coil 112 of a transformer L, the other terminal of the transformer being connected through wire 113 to a third binding post 114 of the timing device C. Wires 115 and 116 connect the binding posts 110 and 114 to the terminals of the control switch M, which may correspond to any one or all of the circuit making and breaking devices 15, 16 and 17 shown in Fig. 2 and hereinabove described. The heating circuit extends from one terminal of the secondary 117 of transformer L through wire 105, the heating elements 101, 102, 103 and 104 arranged in parallel, and wire 106 to one terminal of the rheostat N, the movable contact 118 of which is connected through wire 119 to the other terminal of transformer secondary 117. By properly adjusting the rheostat N, the intensity of the heating current can be varied thus changing the time interval required for heating the thermostatic bar 96 so that it will warp from one of its positions to the other.

70 By adjusting the movable contact 118 in a clockwise direction to its extreme position so as to cut out all of the resistance of the rheostat, the maximum heating current will be obtained and the bar 96 will be heated more rapidly so as to move contact 95 from one end of resistance Y

to the other in a minimum time. When rheostat contact 118 is adjusted in the opposite or counter clockwise direction so as to insert all of the resistance in the heating circuit, the heating current will be diminished so as to heat the bar 96 more slowly and a maximum time will be required to move the contact 95 from one end of resistance Y to the other. For example, in one commercial form of the device the time interval of operation of this resistance mechanism (which as will be hereinafter apparent corresponds to the time interval required for opening the valve) may be varied from a minimum of approximately eight or ten minutes to a maximum of approximately thirty-five minutes. It will be understood that these figures are given merely by way of example, and that the time intervals can be changed by properly designing and proportioning the several elements of the mechanism.

As far as the operation of the timing device C is concerned, it will now be apparent that as long as the control switch M is open no current will flow through the heating circuit, the thermostatic bar 96 will remain in the position shown in solid lines, and all of the resistance Y will be included in the circuit between binding posts 92 and 99, the binding post 91 being shorted directly to the binding post 99 through wire 89, contact 95, thermostatic bar 96, and wire 98. When control switch M is closed, the transformer L will be energized to furnish reduced voltage current to the heating circuit, the intensity of this heating current being determined by the setting of rheostat N. The thermostatic bar 96 will then be gradually heated so as to slowly move the contact 95 along the length of resistance Y, thus inserting a gradually increasing portion of this resistance between the terminals 91 and 99, and gradually decreasing the portion of the resistance in circuit between terminals 99 and 92. When switch M is again opened, the heating circuit will be broken and the parts will gradually cool off so as to return the movable contact 95 to the solid line position shown in the drawings.

The complete operation of the cooperating mechanisms A, B and C can now be described substantially as follows: It will be noted that the reduced voltage current from transformer G, which is delivered to the central terminals 58 and 59, flows through both balanced solenoids H and K, the end terminals of each of these solenoids being bridged across the power terminals 58 and 59. When the mechanisms are in the first inactive position shown in Fig. 1, panel terminal 29 will be shorted to panel terminal 30 through wire 26, resistance terminal 24, movable contact 23, and wire 28. In a similar manner panel terminal 30 is shorted to panel terminal 31 through wire 100, wire 98, thermostatic bar 96, movable contact 95, and wires 89 and 93. The left-hand half of coil 66 of solenoid H is bridged across through the following shunt circuit: From the end terminal of the coil through wires 64 and 68, protective resistance 61, the short circuit previously described between panel terminals 31 and 30, and wire 68 to the central tapped terminal 67 of the coil. In an exactly similar manner the right-hand half of the coil is shunted through the following circuit: From the other end terminal of the coil through wires 65 and 62, protective resistance 63, the previously described short circuit between panel terminals 29 and 30, and wire 68 to the central terminal 67. Since the two protective resistances 61 and 63 are equal, the resistances of these two shunt circuits

will be the same and the same current will flow through all portions of the solenoid coil 66 so that the core 69 will be held in the central neutral position now shown in Fig. 1. Consequently switch J will be in a central and neutral position and no current will flow through the wire 84 extending to the movable contact of this switch from the central terminal 83 of solenoid K. Therefore the same current will flow through all portions of coil 80 of solenoid K and the core 85 of this solenoid will be held in the central or neutral position and switch F will be open so that neither winding of motor A' will be energized and the motor will be at rest.

15 If now the control switch M is closed so as to cause the heating element of timing relay C to be energized, the thermostatic bar 96 will gradually become heated and will warp so as to begin to move the contact 95 along the control resistance Y. The resistances between panel terminals 29 and 30, and 30 and 31 will now no longer be balanced. The terminals 29 and 30 will now be bridged by two shunt circuits, one of which is shorted through resistance device X 20 as already described, and the other of which includes somewhat less than the entire resistance Y. Panel terminals 30 and 31 are bridged by two shunt circuits one of which includes all of the resistance X, and the other of which includes 25 a small portion of resistance Y. It will therefore be seen that the total effective resistance between terminals 29 and 30 will be less than the resistance between terminals 30 and 31. As a result a higher resistance will be bridged across 30 the left-hand half of coil 66 of solenoid H than the resistance bridged across the right-hand half of the coil. Therefore a larger current will flow through the left-hand half of the coil and the core 69 will be drawn toward the left bringing the movable contact 73 of switch J into engagement with fixed contact 74. This will complete a shunt circuit from central terminal 83 of solenoid K through wire 84, protective resistance 84', contacts 73 and 74 of switch J, wire 76, a few end turns of solenoid coil 66, and wires 64 and 81 to the right-hand end terminal of solenoid coil 80. One result of this will be to increase the current flowing through the left-hand end of solenoid H so as to more firmly hold the 40 switch J in the position to which it has just been moved. A second result is to greatly decrease the current flowing through the right-hand half of solenoid coil 80 since this half of the coil is now short-circuited through the shunt circuit last described. As a consequence the core 85 of this solenoid K will be drawn toward the left bringing the contacts 40 and 41 of switch F into engagement thus completing an energizing circuit between terminals 37 and 50 of motor A' so as to cause rotation of the motor in a clockwise direction. This rotation of the motor will start the adjustment of the valve or other device driven by the motor and at the same time will, through crank and lever connections 19, 20 and 65 21 move the contact 23 along the balancing resistance X in a direction away from the terminal 24. When this contact 23 has reached a position on the resistance X corresponding to the position of contact 95 on the control resistance Y the effective resistances across the panel terminals 29, 30 and 30, 31 will again be balanced (since the resistances X and Y are equal and equally distributed throughout their lengths). As a consequence the currents flowing in both 70 halves of solenoid H will again be equalized and

switch J will be returned to its central position so as to break the circuit shunted about one-half of solenoid K which will also be returned to central position so as to open the switch F and stop the motor A'. However, the thermostatic bar 96 will continue to warp so as to move the contact 95 farther away from the end terminal 87 of control resistance Y thus again unbalancing the resistances between panel terminals 29, 30 and 30, 31 so that solenoids H and K 10 and switches F and J will again be moved as before to again complete the motor circuit and cause further rotation of the motor A' in a clockwise direction. This will adjust balancing resistance X so as to again balance the resistances 15 and restore the parts to neutral position thus again stopping the motor. This cycle of events will be successively repeated at intervals until the thermostatic member 96 has reached its extreme position as shown in dotted lines in Fig. 20 1 at which time the motor will have completed the adjustment of the valve 3 or other means driven by the motor.

When the valve or other device is to be returned to its original position, the switch M will 25 be opened so as to break the heating circuit in relay mechanism C. The thermostatic bar 96 will now cool off and gradually return to its original position. As this movement takes place the resistances will be successively unbalanced and 30 balanced as before but in the opposite direction, that is the resistance between panel terminals 29, 30 will at intervals become greater than the resistance between panel terminals 30, 31, as a result of which greater currents will flow in the 35 right-hand halves of solenoids H and K causing the switches J and F to be moved toward the right and causing the motor A' to be energized so as to rotate in a counter clockwise direction. Except for this general reversal in the direction 40 of the several movements, the cycle of operations will be the same as previously described and the valve will be gradually closed, or the equivalent device driven by motor A' will be returned to its original position.

While the rheostat N has been here disclosed as incorporated in the timing mechanism C, it will be apparent that this rheostat, like the switch M, might be located at any accessible location and connected with the timing mechanism by extensions of the wires 106 and 119. This may be desirable in case the timing mechanism is to be located in some relatively inaccessible position, so as to facilitate adjustment of this mechanism for varying the time interval 55 in which the valve is opened.

It will also be apparent that by adding any suitable means for adjusting the proximity of the thermostat 96 to the heaters 101, 102, 103 and 104 it is possible to further vary the time interval 60 required for the opening and closing of the valve.

I claim:

1. Timing mechanism for controlling the operation of an electrically actuated device, said 65 mechanism comprising a circuit including a resistance and a contact movable along the resistance to progressively vary the amount of the resistance effective in the circuit, a thermostatic member for moving the contact, an electric heating element for the thermostatic member, and means for controlling the flow of current through the heating element.

2. Timing mechanism for controlling the operation of an electrically actuated device, said mech- 75

anism comprising a circuit including a resistance and a contact movable along the resistance to progressively vary the amount of the resistance effective in the circuit, a thermostatic member for 5 moving the contact, an electric heating element for the thermostatic member, a circuit for energizing the heating element, and an adjustable rheostat in this circuit.

3. Timing mechanism for controlling the operation of an electrically actuated device, said mechanism comprising a circuit including a resistance and a contact movable along the resistance to progressively vary the amount of the resistance effective in the circuit, a thermostatic member for moving the contact, an electric heating element for the thermostatic member, a circuit for energizing the heating element, an adjustable rheostat in this circuit, and an automatically actuated control switch for the heating circuit.

4. Timing mechanism for controlling the operation of an electrically actuated device, said mechanism comprising a circuit including a resistance and a contact movable along the resistance to progressively vary the amount of the resistance effective in the circuit, a thermostatic bar on which the contact is mounted, an electric heating element for causing the bar to warp to move the contact, and means for controlling the flow 30 of current through the heating element.

5. Timing mechanism for controlling the operation of an electrically actuated device, said mechanism comprising a circuit including a resistance and a contact movable along the resistance to progressively vary the amount of the resistance effective in the circuit, a thermostatic bar on which the contact is mounted, an electric heating element for causing the bar to warp to move the contact, a circuit for energizing the heating 40 element, and an adjustable rheostat in the heating circuit.

6. Mechanism for controlling the time interval of movement of a device comprising a motor for moving the device, an energizing circuit for the 45 motor, a switch in this circuit, electromagnetic means for opening and closing the switch, and circuits for controlling the electromagnetic means comprising a balancing resistance, means operated by the motor for adjusting this resistance, a 50 control resistance comprising a movable contact member for adjusting the effective value of the resistance, a thermostatic member for moving the contact member, an electric heating element for the thermostatic member, a heating circuit for the heating element, and means for controlling the flow of current in this circuit.

7. Mechanism for controlling the time interval of movement of a device comprising a motor for moving the device, an energizing circuit for the 60 motor, a switch in this circuit, electromagnetic means for opening and closing the switch, and circuits for controlling the electromagnetic means comprising a balancing resistance, means operated by the motor for adjusting this resistance, a 65 control resistance comprising a movable contact member for adjusting the effective value of the resistance, a thermostatic member for moving the contact member, an electric heating element for the thermostatic member, a heating circuit for the heating element, and an adjustable rheostat in this circuit.

8. Mechanism for controlling the time interval of movement of a device comprising a reversible motor for moving the device in either direction, a pair of energizing circuits for the motor, one

adapted to cause rotation of the motor in one direction and the other in the opposite direction, a switch member movable in opposite directions from a neutral position to alternatively close either circuit, an electromagnetic means for moving the switch member, and circuits controlling said electromagnetic means comprising a control resistance and a balancing resistance each including a movable contact member for adjusting the effective value of the respective resistance, means 10 for slowly moving the contact of the control resistance, means actuated by the motor for more rapidly moving the contact of the balancing resistance in the same effective direction so as to cause a step by step movement of the motor in 15 a direction determined by the direction of movement of the control resistance contact, the means for moving the control resistance contact comprising a thermostatic member, an electric heating element, a heating circuit for this element, 20 and an adjustable rheostat in the heating circuit.

9. In combination with a heating system comprising a steam supply main, a valve for controlling the flow of steam through the main to the heating system, mechanism for automatically 25 opening and closing the valve, means for automatically imparting predetermined step by step movements to said mechanism with substantial time intervals between said movements so as to slowly move the valve from completely closed to 30 completely open position, and means for selectively timing the length of the intervals between the step by step movements of said mechanism so as to materially change the length of time required for a complete valve movement. 35

10. In combination with a heating system comprising a steam supply main, a valve for controlling the flow of steam through the main to the heating system, an electric motor for opening or closing the valve, mechanism for automatically imparting predetermined step by step movements to said motor with substantial time intervals between said movements so as to slowly move the valve from completely closed to completely open position, and means for selectively timing the length of the intervals between the step by step movements of the motor so as to materially change the length of time required for a complete valve movement.

11. In combination with a heating system comprising a steam supply main, a valve for controlling the flow of steam through the main to the heating system, an electric motor for opening or closing the valve, mechanism for controlling the motor comprising a motor energizing 50 circuit, a switch in this circuit, electromagnetically actuated means for opening and closing the switch, and actuating circuits for the electromagnetic means comprising a control resistance and a balancing resistance in each actuating circuit, 60 means actuated by the motor for adjusting the balancing resistances to intermittently balance the resistances of the actuating circuits, and means for slowly and continuously varying the control resistances. 65

12. In combination with a heating system comprising a steam supply main, a valve for controlling the flow of steam through the main to the heating system, an electric motor for opening or closing the valve, mechanism for controlling the motor comprising a motor energizing circuit, a switch in this circuit, electromagnetically actuated means for opening and closing the switch, actuating circuits for the electromagnetic means comprising a control resistance and a 70

balancing resistance, means actuated by the motor for adjusting the balancing resistance, means for slowly varying the control resistance comprising a movable contact member, a thermostatically operated member for moving the contact, an electric heating element for the thermostatic member, and means for controlling the flow of current through the heating element.

13. In combination with a heating system 10 comprising a steam supply main, a valve for controlling the flow of steam through the main to the heating system, an electric motor for opening or closing the valve, mechanism for controlling the motor comprising a motor energizing circuit, a switch in this circuit, electromagnetically actuated means for opening and closing the switch, actuating circuits for the electro-magnetic means comprising a control resistance and a balancing resistance, means actuated by 15 the motor for adjusting the balancing resistance, means for slowly varying the control resistance comprising a movable contact member, a thermostatically operated member for moving the contact, an electric heating element for the thermostatic member, a circuit for energizing the heating element, and an adjustable rheostat in this circuit.

14. Mechanism for controlling the time interval of movement of a device comprising a reversible motor for moving the device in either direction, a pair of energizing circuits for the motor one adapted to cause rotation of the motor in one direction and the other in the opposite direction, a switch member movable from a neutral position to alternatively close either circuit, an electro-magnetic means for moving the switch member, a pair of actuating circuits for the electro-magnetic means, a control resistance and a balancing resistance included in these actuating circuits, a pair of movable contact members one movable lengthwise of each resistance to divide the resistance into two effective portions, one portion in each actuating circuit, means for slowly and continuously moving the contact of the control resistance from one end of the resistance to the other to progressively unbalance the circuits, and means actuated by the motor to more rapidly but intermittently move the contact of the balancing resistance to intermittently balance the circuits, thus causing a step by step movement of the motor in a direction determined by the direction of continuous movement of the control resistance contact.

15. Mechanism for controlling the time interval of movement of a device comprising a reversible motor for moving the device in either direction, a pair of energizing circuits for the motor one adapted to cause rotation of the motor in one direction and the other in the opposite direction, a switch member movable from a neutral position to alternatively close either circuit, an electro-magnetic means for moving the switch member, a pair of actuating circuits for the electro-magnetic means, a control resistance and a balancing resistance included in these actuating circuits, a pair of movable contact members, one movable lengthwise of each resistance to divide the resistance into two effective portions, one portion in each actuating circuit, thermostatically operated means for slowly and continuously moving the contact of the control resistance from one end of the resistance to the other to progressively unbalance the circuits, and means actuated by the motor to more rapidly but intermittently move the contact of the balancing

resistance to intermittently balance the circuits, thus causing a step by step movement of the motor in a direction determined by the direction of continuous movement of the control resistance contact.

16. Mechanism for controlling the time interval of movement of a device comprising a reversible motor for moving the device in either direction, a pair of energizing circuits for the motor one adapted to cause rotation of the motor 10 in one direction and the other in the opposite direction, a switch member movable from a neutral position to alternatively close either circuit, an electro-magnetic means for moving the switch member, a pair of actuating circuits for the electro-magnetic means, a control resistance and a balancing resistance included in these actuating circuits, a pair of movable contact members one movable lengthwise of each resistance to divide the resistance into two effective portions, one portion in each actuating circuit, means for slowly and continuously moving the contact of the control resistance from one end of the resistance to the other to progressively unbalance the circuits, and means actuated by the motor to more 15 rapidly but intermittently move the contact of the balancing resistance to intermittently balance the circuits, thus causing a step by step movement of the motor in a direction determined by the direction of continuous movement of the control resistance contact, the means for moving the control resistance contact comprising a thermostatic member on which the contact is mounted, an electric heating element for the thermostatic member, a heating circuit for the heating element, and means for regulating the flow of current in this heating circuit.

17. Mechanism for controlling the time interval of movement of a device comprising a reversible motor for moving the device in either direction, a pair of energizing circuits for the motor one adapted to cause rotation of the motor in one direction and the other in the opposite direction, a switch member movable from a neutral position to alternatively close either circuit, an electro-magnetic means for moving the switch member, a pair of actuating circuits for the electro-magnetic means, each actuating circuit including a control resistance and a balancing resistance, automatically operating means 50 for slowly and continuously increasing one control resistance and decreasing the other to unbalance the circuits and cause the switch to be closed and energize the motor, and means actuated by the motor at a more rapid rate to intermittently change the relative values of the balancing resistances to intermittently balance the circuits and open the switch, thus causing a step by step movement of the device.

18. Mechanism for controlling the time interval 60 of movement of a device comprising a reversible motor for moving the device in either direction, a pair of energizing circuits for the motor one adapted to cause rotation of the motor in one direction and the other in the opposite direction, 65 a switch member movable from a neutral position to alternatively close either circuit, an electro-magnetic means for moving the switch member, a pair of actuating circuits for the electro-magnetic means, each actuating circuit including a control resistance and a balancing resistance, automatically operating thermostatic means 70 for slowly and continuously increasing one control resistance and decreasing the other to unbalance the circuits and cause the switch to be 75

closed and energize the motor, and means actuated by the motor at a more rapid rate to intermittently change the relative values of the balancing resistances to intermittently balance the circuits and open the switch, thus causing a step by step movement of the device.

19. In combination with a heating system comprising a steam supply main, a valve for controlling the flow of steam through the main to the heating system, mechanism for automatically opening and closing the valve, means for automatically causing a predetermined step by step operation of said mechanism to gradually move the valve from completely closed to completely open position, and means comprising an electrically heated thermostat for selectively timing

the length of the intervals between the step by step movements of said mechanism.

20. In combination with a heating system comprising a steam supply main, a valve for controlling the flow of steam through the main to the heating system, an electric motor for opening or closing the valve, mechanism for automatically causing a predetermined step by step movement of the motor to gradually move the valve from completely closed to completely open position, and means comprising an electrically heated thermostat for selectively timing the length of the intervals between the step by step movements of the motor. 5 10 15
